UNITED STATES PATENT OFFICE.

HAROLD W. BENNET, OF EVANSTON, ILLINOIS.

POCKET BRIDGE-SCORE.

986,675.

Specification of Letters Patent. Patented Mar. 14, 1911.

Application filed October 27, 1909. Serial No. 524,789.

To all whom it may concern:

Be it known that I, HAROLD W. BENNET, a citizen of the United States of America, and resident of Evanston, Cook county, Illinois, have invented a certain new and useful Improvement in Pocket Bridge-Scores, of which the following is a specification.

My invention relates to improvements in bridge whist score devices, and has for its object the production of a device by means of which the various elements that go to make up the bridge whist score are combined in a form convenient for use.

A further object is the production of a device that can be cheaply constructed.

These and such other objects as may hereinafter appear are attained by my device, embodiments of which are illustrated in the accompanying drawings, in which—

20 Figure 1 represents a front view of my device. Fig. 2 represents a back view of my device in position on a pencil. Fig. 3 represents a sectional view on the line 3—3 of Fig. 2, looking in the direction indicated by 25 the arrows. Fig. 4 represents a cross-sectional view of a modified form of my device.

Like numerals of reference indicate like parts in the several figures of the drawings.

Referring now to the drawings: 5 represents a cylindrical metallic body closed at one end 6 and slightly tapering at the other end 7, and provided with a central cylindrical bore 8. The central bore is adapted to receive a pencil 9 the point of which may 35 be protected by turning the pencil end for end, the point being contained within the cylinder. On the outer surface of the cylinder, and extending longitudinally thereof, are four lines $a-a$ spaced apart at equal 40 distances from each other and extending entirely about the outer periphery of the cylinder are eleven lines $b-b$ spaced apart at substantially equal distances from each

other. These two sets of lines crossing each other at right angles subdivide the outer 45 surface of the cylinder into a series of rectangular subdivisions $c-c$ in four parallel columns of eleven subdivisions each. Within these spaces or subdivisions are imprinted or stamped various designating words, figures and symbols that go to make up a bridge whist score, but arranged in a new and novel manner, as will be fully set forth later.

It will be understood by those familiar 55 with the game that one of the difficulties in arranging a convenient score is the fact that in addition to the suit values a different set of values is given for no trump, and the various honor values in the individual suits 60 are greatly in excess of those in "no trump". In order to overcome these obstacles and provide a convenient and systematic table of scores or values, I enter in the first peripheral series of subdivisions the following 65 four "no trump" values:

No Trump	3 Aces	4 Aces	4 Aces 1 hand
Tk. 12	30	40	100

70

This completes the "no trump" values, and leaves the balance of the subdivisions for the four suits. So in the next or second peripheral row of subdivisions I place the 75 following: A large representation of a heart, a club, a diamond and a spade, and having within the lines of the figures the following legends:

In the heart—1 trick 8; in the club—80 1 trick 4; in the diamond—1 trick 6; in the spade—1 trick 2. This completes the values of the tricks.

In the nine spaces or subdivisions below the heart, I place the honor values that obtain when hearts are trumps, as follows:

3 Hon.	4 Hon.	5 Hon.	4 Hon. 1 hand	5 Hon. 1 in part	5 Hon. 1 hand	Gd. Slam	Lt. Slam	Chicane
16	32	40	64	72	80	40	20	16

90 In the nine spaces or subdivisions below the club, the diamond and the spade, I place the corresponding honor values for those suits. Instead of using the symbolic figures for the suit, I may, if desired, use the words "Hearts," "Clubs," "Diamonds," "Spades," but I prefer to use the symbols as shown in the drawings.

In Fig. 4 I have shown a device having a 95 rectangular cross-section, in the use of which the trick and honor values for each suit would be placed on one side, the "no trump" values still occupying the top space or subdivision on each side.

100 The device can be used for a pencil holder or protector, and can also be made smaller.

and mounted as a watch charm, or carried in the pocket.

I am aware that bridge whist scores are printed on cards and the like, but the peculiar arrangement, and its adaptation to a metallic case, has produced a new and useful article of manufacture.

I claim:

As a new article of manufacture, a pocket bridge whist score consisting of a cylindrical body adapted at one end for the reception of a holding device or member and having its surface marked off into panels by a series of vertical lines and a series of intersecting peripheral lines, the top row of panels being provided with characters indicating

the value of tricks and honors in a no-trump play, the next circumferential series of panels being provided each with a symbol indicating one of the four suits and with characters indicating the value of tricks in that suit, and each vertical row of panels below said trump suit panels being provided with characters indicating the value of the various honors and slams and chicane in that particular suit, for the purpose set forth.

Signed by me at Chicago, Illinois, this 18th day of October, 1909.

HAROLD W. BENNET.
